UNITED STATES PATENT OFFICE.

LESSING L. KOLE, OF MILWAUKEE, WISCONSIN.

VANITY CASE ADAPTED TO SEPARATE COMPACTS OF CONTRASTING SHADES.

Application filed January 15, 1927. Serial No. 161,441.

The object of my invention is to provide novel vanity cases and a novel arrangement of compacts or rouge cakes of different shades or colors for use in such vanity cases and to provide other novel details of construction of the plates which carry such compacts or rouge cakes and the ribs used to space the compacts or rouge cakes.

I attain these and other objects of my invention by the devices illustrated in the accompanying drawings, in which—

Figure 1 is a top plan view of my vanity case, with the cover open to show the arrangement of the compacts and showing my improved form of detachable rib;

Fig. 2 is a transverse section through a modified type of compact holder on a line at right angles to the rib 5;

Fig. 3 is a perspective view of the compact carrying plate 4;

Fig. 4 is a perspective view of a cupped form of the plate 4;

Fig. 5 is a top plan view of a form of my invention having a pair of compacts of different shades arranged on the same plate with the dividing rib of the plate omitted;

Fig. 6 is a section on line 6—6 of Fig. 5; and

Fig. 7 is an edge elevation of an improved form of my invention having different types of compacts carried by the same plate and adapted to be placed in any suitably constructed vanity case (not shown):

Fig. 8 is a detail perspective view of rib 10 detached;

Fig. 9 is a top plan view of a vanity case showing the latest improved form of my invention;

Fig. 10 is a detail perspective view of members 14 and 17 removed from the case; and

Fig. 11 is a detail perspective view of a modified form.

Like characters of reference designate like parts in each of the several views.

Referring to the accompanying drawings, I provide a suitable vanity case 1 having a suitable hinged or other cover 2 carrying a suitable mirror 3 such as shown in Fig. 1. I also provide a suitable compact carrying plate 4 having a suitable rib member such as the rib member 5 in Figs. 2 and 3 or member 10 in Fig. 1 or member 8 in Fig. 4, to divide the plate into a plurality of sections. This dividing rib may be positioned either cen-

trally of the plate to divide the plate into a plurality of equal parts or offset from center to divide the plate into a plurality of unequal parts or in any other suitable manner. On one part or section of the plate is a compact or cake of face powder or rouge 6 of one color while on another section or part is a face powder, compact or rouge cake 7 of different shade or color. Or on one part of the plate a compact cake may be placed while on the other part is a rouge cake. It is the particular object of my invention, however, to provide the novel arrangement of a single plate carrying compact cakes of different shades or colors, one of which cakes is designed and intended for daytime use while the other shade or color is better adapted and intended for use in the evening or at night. The rib 10 which is detachably mounted in the vanity case 1 is shown detached in Fig. 1. It is provided with a bent end portion 12 to engage one portion of the wall of the vanity case while the other bent end 11, which is resilient, frictionally engages the wall of the vanity case at a point directly opposite to the member 12. This rib 10 may be used with the form of the invention shown in Figs. 5 and 6 to insert in the space 5' to more efficiently space the cakes 6 and 7 apart to prevent the user from accidentally getting the dusting pad on the wrong cake.

Referring to Figs. 2 and 3. In this form of the invention I provide a celluloid or similar rib 5 the flanges 13 of which may be glued or otherwise suitably affixed to the plate 4.

Referring to Fig. 4. There is illustrated a modified form of compact holding plate which has the upstanding rib 8 at right angles to the plate, and which is also provided with an upstanding flange or cup 14.

It is within the contemplation of my invention to provide any suitable upstanding member to divide the plate into any suitable plurality of parts, whether the division rib 5 be an attached crimped part as in Fig. 3, a turned up piece 8 as in Fig. 4, or a piece similar to Fig. 4 but glued, soldered, riveted or otherwise fastened to the plate 4.

Referring to Figs. 5 and 6, showing an improved form of my invention, it is within the contemplation of my invention to omit the dividing rib entirely and mount the two types or shades of compacts, cakes of

rouge or the like, of contrasting colors, on the plate 4 with a spacing groove as at 5' in Fig. 5.

I may also provide holes or apertures 9 in any or all of the plates 4 in order that the compacts or cakes of powder or rouge may more securely adhere to the plate.

Referring to Fig. 7 illustrating another improved form of my invention, I provide 10 compacts of different shades; or a compact and a rouge cake; or rouge cakes of different shades, arranged on opposite sides of a plate 4 in the manner illustrated in Fig. 7, and mount such plate in any suitable vanity 15 case (not shown). In Fig. 7 the plate is perforated.

It is within the contemplation of my invention to provide either two shades of rouge, two shades of powder, or rouge and powder 20 on a compact carrying plate or flat base; in other words to provide a plurality of contrasting cakes or compacts of the diverse character described, particularly with a view of having one compact of one shade suitable 25 for use in the day and another compact of a different shade for use in the evening, both carried on the same base in a single vanity case; and it is also within the contemplation 30 of my invention to either have these two or more contrasting cakes or compacts of either equal size or of unequal size and to occupy either all or only a part of the space in the vanity case according to which may be found to make the more attractive and useful vanity case.

It will be noted that the purpose of having the holes punched in the compact carrying plate or base 4 is to prevent the rouge or compact from breaking off from the plate 40 or base 4. These holes or apertures 9 act as a pier for the powder, since when the unit is compressed the cake of powder or rouge is forced into these holes and the perforated base acts as a foundation so that the rouge or compact cannot easily break off. 45 The holes or apertures 9 may be provided in any or all of the plates 4 in any of the several forms of my invention illustrated in the accompanying drawings, the holes or apertures being the same as shown in Fig. 5.

The term "compact" as used in the following claims shall be construed to include both cakes of face powder and cakes of rouge.

It is within the contemplation of my invention to change the form of base 4 from a flat base to a suitably curved or cupped base whereby to more firmly hold the compact on the base, at the same time utilizing either the rib 5, rib 8, or rib 10 and the dividing 55 space 5' as a separating element for the con-

trasting shades of compacts carried by the same base.

Referring to Figs. 9 and 10.

I provide a plate 14 similar to the plate 4 and the other forms except that it has bars 65 of punched up tongues arranged on opposite sides of the plate with a space 16 between said tongues 15 to receive the L-shaped ends 18 or a dividing bar 17.

This form of the invention is relatively 70 simple to manufacture and the L-shaped form of the tongues provides a positive means for locking the dividing bar 17 in place between the tongues 15. It is of course within the contemplation of my invention to position this dividing bar 17 to divide the plate into either equal portions or unequal portions as desired and for the purposes heretofore explained with the other forms of my invention.

Referring to Fig. 11 there is illustrated a modified form closely related to the forms shown in Figs. 9 and 10 except that the bar 19 which is substituted for the bar 17 has no L-shaped ends 18 to extend clear across 80 to the wall of the vanity case in which the plate 14 is removably mounted.

The plates 14 may be provided with perforations to permit of more securely compressing the cakes of powder or rouge onto 90 the plates if such construction is preferred.

What I claim is—

1. In a vanity case of the class described, the combination of a base plate, cakes of powder or rouge of contrasting shades, and 95 the said plate having apertures adapted to cause the compacts to adhere firmly to the plate.

2. In a vanity case of the class described, the combination of a perforated plate, a plurality of slightly spaced compacts of differing shades mounted on the perforated plate, a vanity case in which the compact plate is removably mounted, a rib member having bent end portions to form contact 100 members adapted to frictionally and resiliently engage the walls of the vanity case, said rib member being disposed between the spaced compacts.

3. In a vanity case of the class described, 110 the combination of a plate, a plurality of slightly spaced compacts of differing shades mounted on the plate, a vanity case in which the compact plate is removably mounted, a rib member having bent end portions to form contact members adapted to frictionally engage the walls of the vanity case, said rib member being disposed between the spaced compacts.

LESSING L. KOLE.
